By *John W. Denhard*

UNITED STATES PATENT OFFICE.

HARRY W. DENHARD, OF SAN FRANCISCO, CALIFORNIA, ASSIGNOR TO THE CUTLER-HAMMER MFG. CO., OF MILWAUKEE, WISCONSIN, A CORPORATION OF WISCONSIN.

ELECTRIC ATTACHMENT-PLUG.

1,259,609.

Specification of Letters Patent. Patented Mar. 19, 1918.

Application filed October 31, 1911. Serial No. 657,810.

To all whom it may concern:

Be it known that I, HARRY W. DENHARD, a citizen of the United States, residing at San Francisco, in the county of San Francisco and State of California, have invented new and useful Improvements in Electric Attachment-Plugs, of which the following is a full, clear, concise, and exact description, reference being had to the accompanying drawing, forming a part of this specification.

This invention relates to electric attachment plugs.

In the construction of electric attachment plugs it is important that a small number of simple parts be used in order that the plug may be easily manufactured and readily assembled. It is further important that the parts be rugged, be firmly held in position and that all strain be relieved from the point of attachment of the electrical conductors to the contacts of the plug.

One of the objects of the present invention is to provide an improved and simplified construction of electric attachment plug.

Another object is to provide an improved plug made of a minimum number of simple parts.

30 A further object is to provide a simple plug having improved means for removing strain from the plug contacts.

Other objects and advantages of the invention will hereinafter appear.

35 The accompanying drawings illustrate an embodiment of the invention.

The views of said drawings are as follows:

Figure 1 shows a side elevation of this 40 form of attachment plug;

Fig. 2 shows a central longitudinal sectional view on line 2—2 of Fig. 1;

Fig. 3 shows a contact carrying part of the attachment 1 $\frac{1}{2}$ in elevation;

45 Fig. 4 shows detail view of the base members.

In these drawings, I have illustrated an attachment plug formed in two parts, 1 and 2, which are substantially identical in 50 conformation. These parts 1 and 2 are preferably formed of insulating material and inclose between them the contact clips. These base members are inclosed in an outer metallic casing 3 having a swivel cap 4 extending through an opening 5 in one of the

ends of the same. The opposite end of the casing 3 is open as shown in Fig. 2. The conductors 6 are led into the swivel cap 4 through a helically coiled spring 7, as described in my copending application Serial 60 No. 605,344, filed January 30th, 1911. The two base members 1 and 2 are secured with-in the casing 3 by a suitable bolt or screw 8.

The base members 1 and 2 are preferably provided with a recessed inner surface 9 separated by septums 10 and provided with a plurality of spaced inwardly extending studs 11 at the back of the same. The bottom of the recess 9 around the studs 11 is slightly dished out as shown in Fig. 4. The 70 septum 10 on each base member is preferably provided with an enlarged substantially rectangular shaped inner end 12, through which the bolt or screw 8 extends, and an elongated rounded outer portion 75 connected to the rectangular portion by a reduced neck 13. The conductors 6 are preferably brought in as shown in Fig. 3 and wound around the studs 11, the conductors being passed on one side of one 80 stud and then around under that stud and over the other stud where they are connected to contact members 14.

These contact members 14 are each preferably formed of a single strip of metal so 85 doubled or bent as to provide spring contact clips 15, which extend through the openings in the opposite ends of the base members on opposite sides of the septum 10. One of the legs of each contact member is provided with an extension 16 arranged to fit into the recesses on the sides of the reduced neck 13 of the septum, while the other leg of each contact member is arranged to fit snugly around a shoulder 17 on the base members. The ends of the conductors 6 are preferably attached to the inner overturned or doubled ends of the contact members 14 at points between the studs 11 and the shoulders 17. These conductors are attached by means of suitable binding screws 18, the outer ends of which are housed in suitable recesses 19 formed in the base member.

It will thus be seen that an improved attachment plug has been provided which is made of a small number of simple parts. These parts may be easily and inexpensively manufactured and readily assembled. The contact members are mounted in the base so 105 110

that they are rigidly held therein without the use of special fastenings and the base is constructed so as to thoroughly insulate the contacts and at the same time allow sufficient movement of the resilient parts of the contacts to obtain good engagement with the coöperating plug members. The base is provided with an efficient means for relieving the strain at the point of attachment of the electric conductors to the contact clips. This means is formed integral with the base and permits the conductors to be readily wound thereabout before the plug is assembled. The whole structure is such that the parts are readily accessible by merely loosening a single screw which holds the two parts of the base together.

It should be understood that the construction shown is for purposes of illustration only and that other structures may be devised which embody the invention and which come within the spirit and scope of the appended claims.

Having thus described my invention, what I claim as new and desire to secure by Letters Patent, is:

1. In an electric attachment plug, a two-part insulating base having recessed adjacent faces, spaced studs about which the line conductors may be wound, and a plurality of recesses separated by septums arranged to receive the contact members.

2. In an electric attachment plug, a two-part base having its abutting faces recessed and provided with a plurality of registering studs, septums extending substantially at right angles to a line joining said studs, and contact clips carried between said parts and on opposite sides of said septums.

3. An electric attachment plug provided with an insulating base made in two parts having the adjacent surfaces thereof provided with coöperating recesses, contact clips arranged in said recesses, said recesses and clips being shaped so that said clips are held in position without the use of fastening means, and studs within the recess of one of said parts coöperating with studs in the recess of the other part to form means about which electrical conductors may be wound for relieving the stress at the point of attachment of the conductors to the contact clips.

4. An attachment plug having a base comprising a pair of blocks of insulating material, a casing fitting over said base, recesses in the adjacent faces of said blocks forming irregular passages through said base, a contact clip shaped to fit in each recess, means for holding the blocks together whereby when the plug is assembled the clips are held against both lateral and longitudinal bodily movement, and co-operating studs in the recesses of said blocks forming bars across said passages around which the conductors may be wound to relieve the strain on the points of attachment of said conductors to the contact clips.

5. In an electric attachment plug, a two-part base having recessed adjacent surfaces and a plurality of spaced studs at one end of the same, conductors coiled about said studs, and contact clips carried between the parts of said base and attached to said conductors.

6. In an electric attachment plug, a two-part base, each of said parts being recessed, a plurality of studs in said recess and a septum extending substantially at a right angle to the line joining said studs, and contact clips carried between said parts on opposite sides of said septum.

7. In an electric attachment plug, a two-part base having recessed adjacent faces and provided with a plurality of spaced studs at one end and a septum at the other, conductors wound about said studs, and contact clips fitting in irregularly-shaped recesses on the opposite sides of said septum and connected to said conductors.

8. In an electric attachment plug, a base and a plurality of resilient contact clips lying in correspondingly-shaped recesses in said base, each clip comprising a doubled over strip of metal bent to insure positive engagement with the walls of said recess and having its ends spread apart to receive the plug contact.

In witness whereof, I have hereunto subscribed my name in the presence of two witnesses.

HARRY W. DENHARD.
